CELERY AND OLIVE DISPENSER

Gerard X. Foley, Boston, Mass.

Application December 26, 1957, Serial No. 49,038

Term of patent 14 years

(Cl. D44—24)

FIG. 1

FIG. 2

Figure 1 is a top plan view of a celery and olive dispenser, showing my new design;

Figure 2 is an elevational view thereof, with a supreme dish in dotted outline for the purpose of illustration.

I claim:

The ornamental design for a celery and olive dispenser, as shown and described.
